UNITED STATES PATENT OFFICE.

WILLIAM HENRY GALVIN, OF OMAHA, NEBRASKA.

SMOKING-PIPE.

1,046,383.

specification of Letters Patent.

Patented Dec. 3, 1912.

Application filed February 14, 1912, Serial No. 677,494. Renewed October 24, 1912. Serial No. 727,561.

To all whom it may concern:

Be it known that I, WILLIAM HENRY GALVIN, a citizen of the United States, and a resident of Omaha, in the county of Douglas and State of Nebraska, have invented certain new and useful Improvements in Smoking-Pipes, of which the following is a specification, reference being had to the accompanying drawings.

This invention relates to certain new and useful improvements in smoking pipes, and the object of my invention is to provide a smoking pipe including a removable foraminous plate which is held a suitable distance above the bottom of the pipe and above the draft opening leading into the stem, so that a chamber is provided below the disk into which any saliva entering the stem will drain.

Another object is to provide a pipe of a simple and inexpensive nature and of a durable construction including a removable tobacco carrying plate which shall be capable of convenient adjustment in position within the pipe bowl in a manner to prevent the saliva draining into the bowl coming in contact with the tobacco.

A further object is to provide a suitable pipe with a foraminous tobacco supporting disk having a notched circumscribing spring flange insuring the disk being held within the pipe bowl in spring pressed condition, thereby preventing casual displacement of the disk, the disk further, in being withdrawn from the bowl, abrading the inner surface of the pipe, thereby cleaning the same.

With these and other objects in view, the present invention consists in the combination and arrangement of parts as will be hereinafter more fully described and finally pointed out in the appended claim, it being further understood that changes in the specific structure shown and described may be made within the scope of the claim without departing from the spirit of the invention.

In the accompanying drawings forming a part of this specification, and in which like numerals of reference indicate similar parts in the several views: Figure 1 is an elevational view of the pipe embodying my invention, disclosing the bowl in section. Fig. 2 is a top view of the pipe with a portion of the stem removed. Fig. 3 is a section on line 3, 3 of Fig. 1. Fig. 4 shows an elevational detail of the tobacco carrying disk.

Fig. 5 shows a detached detail of the pipe bowl.

In my present invention I provide a tobacco pipe so constructed that the tobacco within the same will be held upon the removable foraminous disk located a suitable distance above the bottom of the pipe so that there is provided an air chamber below the tobacco holding member which further serves to receive any saliva that may drain into the pipe bowl. The chamber further serves as a cooling compartment, thereby preventing the lower end of the pipe bowl becoming heated.

In the accompanying drawings, the numeral 1 designates a suitable pipe bowl having a cylindrical opening 7. The lower end 2 of the bowl is preferably provided with an exterior screw thread to receive a cap 15. This cap may be of metal or any other suitable material; and is detachably secured to the bottom of the pipe bowl, as shown in Fig. 1. Near the lower end, the pipe bowl is provided with the stem aperture 3, while located within the upper edge of the bowl are the two oppositely positioned ear openings 4. As shown in Fig. 2, the semi-circular bail seat 5 extends from one ear opening to the other.

Arranged to be removably and frictionally held within the pipe bowl opening 7 is the foraminous disk 8 having the circumscribing notched upstanding resilient flange 9. This flange 9 performs a double function in that it not only holds the disk against casual displacement within the pipe bowl, but in withdrawing the disk from the bowl, this resilient flange 9 shears off the charred inner surface of the pipe bowl, thereby keeping the inner bowl surface clean above the disk. This foraminous disk is held a suitable distance above the stem opening 3 as clearly shown in Fig. 1, and extending from the inner face of this foraminous disk 100 are the two oppositely positioned arms 10, each arm ending in an angular apertured ear 11, within the apertures of which are pivotally held the re-curved ends 12 of the bail 13. This bail is preferably made of spring wire, and is of such size that it requires manual manipulation to force the bail into the seat 5. After being seated, it necessarily requires manual manipulation to unseat the bail. As shown in Fig. 1, the angular apertured ears 11 are arranged to seat within the openings 4.

105
110

In connection with the bowl 1, I have shown a stem 6 which may be of any conventional construction and is arranged to be secured within the opening 3.

5 The pipe is used exactly as any other pipe is used. The smoke, after passing through the foramina of the disk 8 enters the lower portion of the pipe bowl from which it is drawn through the stem 6. As the tobacco 10 is held above the stem opening 3, the saliva entering the pipe bowl will not contact with the tobacco. The pipe is emptied in unscrewing the cap 15. The foraminous disk can be readily kept in a sanitary condition 15 in that the same can easily be withdrawn. The disk edge 9 abrades the inner surface of the pipe bowl and so removes any charred portion above the disk. As the bore within the pipe bowl enlarges in the use of the 20 pipe, the notched disk 9 is flared outward which can be easily done. Under these conditions, the foraminous disk is always tightly held within the pipe bowl, while the bail is securely held within its seat.

25 A pipe constructed according to my invention is simple and inexpensive and both durable and efficient in operation and the adjustment of the foraminous disk within

the pipe bowl or the removal therefrom may be effected with ease, accuracy and despatch. 30

Having thus described my said invention, what I claim as new and desire to secure by United States Letters Patent is:

A smoking pipe including a bowl having a cylindrical opening with a stem aperture 35 positioned near the lower end of the bowl and oppositely positioned ear openings within the upper edge, a semi-circular bail seat extending from one ear opening to the other, of a foraminous disk having a circumscribing 40 notched upstanding resilient flange arranged to be frictionally held within said cylindrical bowl opening above said stem aperture, two oppositely positioned arms secured to said disk each ending in an angular 45 apertured ear, said ears arranged to seat within said openings, and a bail pivotally held to said ears arranged to be sprung into said bail seat, substantially as and for the purpose set forth. 50

In testimony whereof I affix my signature, in presence of two witnesses.

WILLIAM HENRY GALVIN.
